UNITED STATES PATENT OFFICE.

FRANCIS HARRISON AND FRANCIS LESLIE HARRISON, OF PRESTWICK, SCOTLAND.

INCANDESCENT ELECTRIC LAMP.

1,205,737.

Specification of Letters Patent. Patented Nov. 21, 1916.

Application filed October 24, 1913. Serial No. 797,061.

To all whom it may concern:

Be it known that we, FRANCIS HARRISON and FRANCIS LESLIE HARRISON, citizens of the United Kingdom of Great Britain and 5 Ireland, and residents of Pegu, Marina Road, Prestwick, Ayrshire, Scotland, have invented certain new and useful Improvements in or Relating to Incandescent Electric Lamps, of which the following is a specification, such as will enable others skilled 10 in the art to which it appertains to make and use the same.

The present invention relates to incandescent electric lamps of the metallic filament 15 type, in contradistinction to carbon filament lamps, and relates more particularly to the means and method of attachment of the filaments in place and to the provision of such means as will permit of a ready and cheap 20 replacement or renewal of a broken filament, while retaining the original cap, bulb and filament support.

According to one form of our improved 25 method, applied to metal filament lamps, we employ in connection with the usual leading-in wires, supporting wires having their ends bent into a spiral so as to grip the end of the filament, and in the case of two of them to grip the leading-in wire as 30 well. Further in connection with such spring gripping means we prefer in some cases to apply them at the pip end of the lamp and to bring the leading-in wires down the central stem, so as to facilitate renewal 35 when a filament breaks, as will be explained.

We will now describe, with reference to the accompanying drawing, a lamp, according to this invention, comprising central downwardly extending leading-in conduct- 40 ing wires and the spring supporting wires for receiving the ends of the filaments and leading-in wires.

Figure 1 is an elevation of the lamp. Figs. 2 and 3 are detail views, and Fig. 4 45 shows a modified form of filament securing arm.

The central filament supporting portion instead of being made of a short length of tube, through which the leading-in wires 50 pass and project laterally, and a central extension glass rod, to the lower end of which are secured the radial supports for the lower ends of the filaments, is made of one piece of glass tube forming the central support α , 55 through which the conducting wires b pass and join the inner part of the leading-in

wires b' which issue at the lower end of said support. At the upper end of the tube we form a collar or flange c from which extend outwardly a series of supporting 60 arms d , here shown as straight wires with hooked ends d' for receiving the upper parts of the filaments. Near to its lower end the tube α is provided with a series of outwardly extending filament-supporting 65 wires e bent at their outer ends in the form of spirals e^2 , adapted to clamp or pinch the ends of the filaments and also the ends or outer part of the leading-in wires in the case of two of them between their bent por- 70 tions.

In the construction illustrated inverted V-shaped or hairpin filaments f are employed, the filaments being simply hung on the hooks d' while their lower ends are 75 gripped between the bends or spirals of the lower supports e . For this purpose the latter are preferably provided with ends e' projecting parallel with the wire e to act as arms for opening the spring spirals by 80 pressing e and e' together, as shown more clearly in the plan views in Fig. 2 showing the spring in its closed position, and in its open position, i. e. when e and e' are pressed together. The two leading in wires b' are 85 similarly secured to two of the supports so that the circuit through the filaments is completed. The lower end of the tube α may be pinched or flattened. It will thus be seen that in this construction the metallic 90 filament is upside down or reversed as compared with ordinary filament lamps, the object of this arrangement being that should a filament break in use, the lamp can be more easily repaired as will be explained, 95 than would be the case if the ends of the filaments were secured at the cap end of the lamp. To effect such a repair or renewal, the pip on the lamp bulb is removed and air is allowed to enter the bulb. The 100 hole g is then enlarged, say by means of a gas flame, and the fractured filament or filaments removed, and the inner surface of the bulb cleaned if necessary, which can be done by heating the outside of the glass 105 by means of a Bunsen flame. A new filament is then introduced through the hole g by means of a suitable instrument and the bend of the filament hung on the hook d' the two limbs of the filament hanging 110 down freely. To secure these limbs, when they are correctly positioned against their

respective supports *e*, the outer part of the bent or spiral portions *e*² of the latter are opened slightly by pressing *e* and *e'* together as shown in Fig. 2 (which represents 5 a plan view of the wire support shown in Fig. 1 in its normal and opened positions) by means of a small rod or blade introduced through the hole *g* so that the end of the filament passes between the bends of the 10 wire, and on release of the parts *e* and *e'* the filament is firmly gripped to its support. Alternatively the parts *e* and *e'* may be forced apart, as shown in Fig. 3, in which case the inner portion of the spiral will be 15 opened to secure the filament. At 1 in Fig. 4 we have shown a slightly modified construction, the wire support having a hook *e*³, at its outer end, so that on inserting a rod in the hook *e*³ the spire of the spiral 20 can be opened out to receive the filament. A piece of glass tube is then fused to the edge of the holes *g* and the bulb is then exhausted and finished off, in the usual 25 well known manner.

As metal filaments are usually extremely thin and consequently somewhat difficult to see, we prefer to dip the ends of the filament into some coloring matter, such as sealing wax, so that the ends of the filament may 30 be easily located, when they are being secured in place, after which the ends, below the support, carrying the sealing wax are broken off.

The central support may be of any desired 35 shape or cross section and may be of clear white or colored glass or it may be silvered to act as a reflector, the leading in or conducting wires within it being thus hidden from view, and while a tube is probably the simplest and most convenient device for bringing the leading-in wires to the lower part of the lamp, they could obviously be embedded in glass or other non-conducting material or arranged in grooves 40 in a glass, kaolin or like rod or support, or be carried down the outside of the support.

While we have referred to hairpin fila-

ments, we may use a length or lengths of flexible metal filament which is bent over 50 the hooked supports at the cap end of the lamp and then secured to the lower spring support and so on.

In some cases, for instance when comparatively thick filaments for carrying a 55 heavy current are used, we may attach to the end of the filament a piece of conducting wire, which in turn is secured to the spring supporting wire.

While we have stated that the hole, for 60 repair purposes is made at the pip of the bulb, it can be made at another part if such would be more advantageous for easy access to the particular part to be renewed.

What we claim and desire to secure by 65 Letters Patent is:-

1. In an electric lamp, the combination of a leading-in wire; a support supported by the lamp separately from said wire and having a coil formed therein gripping said 70 wire; and a filament also gripped by said coil.

2. In an electric lamp, the combination of a leading-in wire; a support supported by the lamp separately from said wire and 75 having a coil formed therein gripping said wire between adjacent convolutions; and a filament also gripped between adjacent convolutions of said coil.

3. In an electric lamp, the combination of 80 a leading-in wire; a gripping support supported by the lamp separately from said wire and having a coil formed therein gripping said wire between its convolutions and having an extension at its free end for manipulating the gripping support; and a filament also gripped between convolutions of 85 said coil.

In witness whereof we have hereunto set our hands in presence of two witnesses.

FRANCIS HARRISON.

FRANCIS LESLIE HARRISON.
